UNITED STATES PATENT OFFICE.

JOHN H. WENZLICK, OF WHEELING, WEST VIRGINIA.

SUPPORTING-CHAIR FOR DRILL-BOXINGS.

1,377,296.

Specification of Letters Patent. Patented May 10, 1921.

Application filed May 21, 1920. Serial No. 383,312.

To all whom it may concern:

Be it known that I, JOHN H. WENZLICK, a citizen of the United States of America, and resident of Wheeling, county of Ohio, 5 and State of West Virginia, have invented certain new and useful Improvements in Supporting-Chairs for Drill-Boxings, of which the following is a specification.

This invention relates broadly to adjustable supports for miners' drills or augers, and more particularly to a chair structure for the support of the bearings or boxings in which such drills or augers are carried.

The primary object of the invention is to 15 provide a supporting chair of the adjustable sliding type which has the opposite body members thereof disposed in flexible connected relation so that they will automatically adjust themselves to variations in the

20 distance between the upright side-bars or supporting posts by which they are carried.

A further object is to provide a chair of the character mentioned having separable body members having connecting means 25 which allows said members sufficient relative play or movement to adopt themselves to any irregularities in the side-bars, thus insuring a free and easy, or non-binding, movement during adjustment of the chair.

30 In describing the invention in detail, reference is herein had to the accompanying drawings, in which—

Figure 1 is a front elevation of the invention;

35 Fig. 2 is a central vertical section of the same; and—

Fig. 3 is a side elevation.

Referring to said drawings, 1 and 2 indicate two oppositely disposed body members 40 adapted to be slidably mounted upon the parallel upright relatively-spaced side-bars which constitute the usual supporting posts for the drill. Said members have their outer faces formed with vertically disposed 45 ribs 3 designed to seat within the longitudinal channels commonly provided in the inner or confronting faces of the side bars and have cages 4 and 5 formed at their upper and lower ends, respectively, in which

50 said side-bars are received. The cages 5 carry projecting boss-like portions 6 which are interiorly threaded for the reception of set-screws whereby the chair is secured in adjusted position upon the side-bars.

55 As chairs of this general type have heretofore been constructed, the two body mem-

bers and the connecting rod or bar have been cast in an integral one-piece structure. Such integral construction is objectionable for the reason that the body members are inflexibly related and, consequently, when irregularities in the side-bars or variations in the distance between the side-bars are encountered, the chair naturally binds upon the side-bars to the extent that adjustment 65 is rendered difficult. The objection noted is obviated in the present device by the provision of means whereby the opposite body members 1 and 2 are relatively secured together in spaced relation and, at the same 70 time, are capable of a limited range of free and independent movement which allows said parts to accommodate themselves to such slight irregularities in form and variations in the spacing of the side-bars as is 75 commonly encountered in adjusting chairs on such side-bars. Said securing means comprises a horizontal arm or tie-rod 7 rigidly carried by or formed integral with one of the body members, as 1, at a point 80 approximately midway between the ends of the latter. Said rod has the outer end thereof reduced to form a neck portion 8 and is terminated by a head 9 of oblong form. Said reduced neck is designed to fit loosely within 85 an oblong hole 10 provided in the body member 2. The hole 10 has its greatest diameter extending substantially at right angles to the greatest diameter of the head 9 when the said body members occupy their 90 normal relative positions, so that said members will be securely connected against chance separation. The said head 9 and hole 10 substantially correspond in size and form so that the former may be readily introduced through the latter when one of said members is disposed in a position approximately at right angles to the other, as indicated in dotted lines in Fig. 3.

Due to the loose fit of the neck 8 of the 100 tie-rod 7 in the hole 10 of the member 2, each of the members 1 and 2 is obviously more or less free to move with respect to the other for the purpose hereinbefore referred to.

105 Provided in the inner faces of the opposite cages 4 of each of the body members is a recess or seat 11, the opposite seats constituting bearings for the trunnions of the boxings in which the drill shank is carried. 110 Similar seats or bearings 12 are provided in the inner faces of the cages 5, said bear-

ings being designed for use when the chair occupies a reversed position.

Formed on the front faces of the cages 4 are projecting portions 13 having bearings 14 therein adapted for the reception of boxing trunnions of a length greater than those for which the bearings 11 and 12 are designed.

What is claimed is—

- 10 1. A supporting chair for miners' drills, comprising body members adapted for adjustment upon the bars of a supporting post, means whereby said members are held in spaced relation and are allowed a limited range of independent free movement, said means comprising a transverse connecting element having fixed relation at one end with one of said members and having its opposite end headed and forming a flexible joint with the other member.
- 15 2. A supporting chair for miners' drills, comprising body members adapted for adjustment upon the bars of a supporting post, and means whereby said members are detachably connected, said means comprising a tie-rod rigidly carried by one of said members and arranged to form a flexible joint with the other member.
- 20 3. A supporting chair for miners' drills, comprising body members adapted for adjustment upon the bars of a supporting post,

and means whereby said members are detachably connected, said means comprising a tie-rod rigidly carried by one of said members, said rod having an oblong head 35 upon its end and projected through an oblong hole in the opposite member, said head and said hole being normally disposed in such relation that the greatest diameter of the former crosses the greatest diameter of 4 the latter.

4. A supporting chair for miners' drills, comprising body members adapted for adjustment upon the bars of a supporting post, and means whereby said members are detachably connected, said means comprising a tie-rod rigidly carried by one of said members, said rod having a reduced neck terminating in a head of oblong form, said neck being loosely received in an oblong hole provided in the other member, said hole being of a size and form to permit of the passage therethrough of said head when said members are relatively disposed at an angle in which they are inoperative. 50 55

In testimony whereof, I affix my signature in presence of two subscribing witnesses.

JOHN H. WENZLICK.
